UNITED STATES PATENT OFFICE.

OSCAR WOODWARD, OF NEW YORK, N. Y., ASSIGNOR TO WYCKOFF, SEAMANS & BENEDICT, OF ILION, NEW YORK, A CORPORATION OF NEW YORK.

TYPE-WRITING MACHINE.

No. 918,938.

Specification of Letters Patent. Patented April 20, 1909.

Application filed January 26, 1906. Serial No. 297,964.

To all whom it may concern:

Be it known that I, OSCAR WOODWARD, citizen of the United States, and resident of the borough of Manhattan, city of New York, in the county of New York and State of New York, have invented certain new and useful Improvements in Type-Writing Machines, of which the following is a specification.

10 My invention relates to typewriting machines and more particularly to line spacing mechanism, and the object of said invention is to provide efficient mechanism of the character specified.

15 To the above and other ends which will hereinafter appear, my invention consists in the features of construction, arrangements of parts and combinations of devices to be hereinafter described and particularly pointed out in the appended claims.

20 In the drawings, wherein like reference characters indicate corresponding parts in the various views, Figure 1 is a fragmentary side elevation of the upper portion of one 25 form of typewriting machine showing my invention applied thereto; the right hand finger wheel being sectioned away on a line $r-r$ of Fig 2. Fig. 2 is a fragmentary plan view of the same. Fig. 3 is a fragmentary 30 front elevation of the parts shown in Fig. 2; the top plate being shown in section on the line $w-w$ of Fig. 2. Fig. 4 is a detail side view of the line spacing pawl-carrier and the adjusting plate which co-operates there- 35 with to regulate the extent of movement of the carrier; the view showing the parts as they appear when looking from left to right. Fig. 5 is a fragmentary, detail, vertical, sectional view taken on the line $x-x$ 40 of Fig. 2 and looking in the direction of the arrow at said line. Fig. 6 is a detail, vertical, sectional view taken on a line $r-r$ of Fig. 2 and looking in the direction of the arrow at said line; the carriage being omitted 45 and the parts shown in the positions they assume at the last part of the line spacing movement. Figs. 7 and 8 are views corresponding substantially to Fig. 6 except that the parts are shown in different posi- 50 tions. Fig. 9 is a detail, longitudinal, vertical sectional view showing the manner of mounting the rock shaft. Fig. 10 is an enlarged detail face view of the angular lever for actuating the line spacing pawl. Fig. 55 11 is a transverse sectional view of the same,

the section being taken through the slotted arm of the lever. Fig. 12 is an enlarged detail front view, with parts in section, of a portion of the line spacing mechanism. Fig. 13 is an enlarged detail side view of the crank arm for actuating the line spacing mechanism, with the ball member of the universal joint mounted thereon. Fig. 14 is a detail side view of another form of locking device for the regulating plate. 65

I have shown my invention in the present instance applied to a front-strike typewriting machine. It should be understood, however, that the line spacing mechanism forming the subject-matter of the present invention may be applied to various forms of typewriting machines. 70

The top plate 1 of the machine is supported on corner posts 2 and has upwardly extending lugs 3 that support fixed carriage 75 rails 4 having substantially V-shaped bearing faces that co-operate with crossed anti-friction rollers 5. The rollers 5 likewise co-operate with substantially V-shaped tracks 6 on a carriage 7 in order to support it in its 80 travel from side to side of the machine. A vertically movable shift rail 8 receives its vertical movement through a rod or rods 9 that are actuated by any suitable shift key. The shift rail 8 supports a grooved roller 10 85 which is connected to a platen frame by a screw pivot 12. The platen frame is connected to the carriage by parallel links 13, 14, each of the links 13 being pivotally connected to a side plate 11 of the platen frame 90 at 15 and to the carriage at 16. Each link 14 is in a like manner pivoted at 17 to a side plate of the platen frame and is pivoted at 18 to a depending arm 19 on the carriage. The side plates 11 have bearing openings 95 therein for the reception of a platen shaft 21 on which a platen 22 is mounted.

A line spacing ratchet wheel 23 is secured at the right hand end of the platen and a detent roller 24 of the usual construction bears 100 against the teeth 25 of the line spacing wheel to maintain the wheel against accidental displacement in the position to which it is moved by the line spacing mechanism. This detent roller is mounted upon the forward 105 end of a flat spring 26, the rear end of the spring being secured to the platen frame by a screw 27. The right hand side of the carriage is provided with a bearing 28 that may be formed integral with the carriage and 110

has a central bore for the reception of a rock shaft 29 which extends at its rear end beyond the bearing and has secured to it a crank arm 30. This crank arm is in the nature of a cylindrical pin which projects from a collar 31 that is apertured at 32 for the reception of a pin 33 which passes through the openings 32 and through a transverse opening in the shaft 29 to rigidly connect the crank arm 30 to the rock shaft.

The bore in the bearing 28 is enlarged at 34 (Fig. 9) for the reception of a coiled restoring spring 35 which surrounds the rock shaft 29 and one end 36 of which is seated in an opening 37 in the bearing. The other end 38 of the spring is seated in an opening 39 in a bearing sleeve or collar 40. The central bore in this collar receives the rock shaft and a reduced portion 41 of the sleeve is received and seated within the bore 34 in the bearing 28, so as to turn therein. A shoulder 40^a formed at the junction of the enlarged and reduced portions of the sleeve is adapted to bear against one end of the bearing 28. A set screw 42 extends through a threaded opening in the sleeve 40 and bears at its inner end against the rock shaft 29 so as to rigidly connect the sleeve to the rock shaft. A circumferential shoulder 43 is formed on the rock shaft and bears against the sleeve 40. It will be seen that from this construction the parts can be readily assembled or disconnected when desired and that the collar 31 and sleeve 40 prevent the longitudinal movement of the rock shaft 29 in its bearing; that the restoring spring 35 is housed within the bearing 28; that the construction presents a neat appearance; and strong and efficient means for transmitting movement to the line spacing pawl are provided as will hereinafter more clearly appear.

The forward end of the rock shaft 29 has a downwardly extending crank arm 44 with a finger piece 45 at the free end thereof. The disposition of this crank arm is such that the pressure exerted from left to right thereon tends to turn the rock shaft 29 and thereby actuate the line spacing mechanism and at the same time to return the carriage to the right across the top plate to begin a new line of writing. The cylindrical pin or crank arm 30 hereinbefore referred to carries one member 46 of a universal or ball and socket joint. The member 46 constitutes a spherical head which is perforated in order that it may be mounted to turn and to slide longitudinally on the pin or crank arm 30 and constitute in effect an anti-friction roller as well as one member of a universal joint (Fig. 18). This ball is adapted to be received in an elongated opening or slot 47 in an angle lever 50, said slot having undercut walls 48 that are curved to correspond to the curvature of the ball

which is received therein, as clearly indicated in Fig. 11. The ball 46 may be introduced into its bearing slot 47 through an enlarged opening 49 at one end of the slot 47 and when centrally positioned 70 in the enlarged opening, may be moved longitudinally along the slot 47 so as to be seated within the combined socket and slide-way formed by the grooved walls 48 of the slot. It will be understood that in the operation of the machine the ball 46 never passes to a point where it will register with the enlarged opening 49 and there is no liability therefore of the parts being accidentally disconnected. The angular lever 80 50 is pivoted at 51 to the right hand end of the carriage, and the upwardly and forwardly extending arm thereof is pivoted at 52 to a rearwardly extending link 53 which, in turn, is pivoted at 54 to a line spacing 85 pawl 55. This line spacing pawl is pivoted intermediate of its ends at 56 to a vibrating line spacing pawl carrier 57 that is adapted to turn on an axis coincident with the axis of the platen. From an examination of 90 Fig. 12 it will be observed that the right-hand end plate 11 of the platen frame has a threaded opening therein which receives a threaded end 58 of a bearing sleeve. This bearing sleeve has an angular or hexagonal 95 portion 59 by means of which the end 58 can be threaded into its opening in the platen frame and the hexagonal portion constitutes a shoulder that is adapted to bear against the outer side of the platen frame. 100 An outwardly extending portion 60 is formed on the sleeve and the central bore extends through the parts 58, 59 and 60 which constitute the sleeve for the reception of the platen shaft. The extension 60 105 passes into an opening 61 formed in the right hand side bar of the carriage and is adapted to co-act with screw stops 62, 63 (Fig. 1) carried by the carriage and limit the upward and downward shifting movement of the platen as it is shifted from upper to lower case and vice versa.

A bearing collar 64 is received on the threaded end 58 of the bearing sleeve as shown in Fig. 12 and bears at its inner 115 end against the right hand side plate 11 of the platen frame and forms a peripheral bearing at 65 for the bearing portion 66 of the line spacing pawl carrier 57. A flange or hexagonal head 67 is formed at one end 120 of the bearing collar 64 so as to co-operate with the bearing portion 66 of the pawl carrier and prevent it from being displaced from its bearing. The head 67 also enables the collar 64 to be readily secured in place 125 on the sleeve 58-59-60 and to lock said sleeve against accidental displacement.

A plate or adjusting device 68 is provided for regulating the extent of line spacing movement of the line spacing pawl 130

and its carrier. This plate is mounted on the peripheral bearing 65 of the sleeve 64 and is situated between the carrier 57 and the right hand end plate 11 of the platen frame. The bearing opening 69 of the regulating plate is enlarged in the direction of the length of the plate as indicated in Figs. 5, 6, 7 and 8 in order to afford a movement of the plate at right angles to or radially of the axis of the platen as well as a turning movement around the peripheral bearing surface 65. The lower end of the plate carries a pin 70 by which one end of a contractile spring 71 may be connected thereto, the other end of the spring being secured to a pin 72 that projects inwardly from the right hand end plate 11 of the platen frame. The upper end of the regulating plate 68 is provided with a finger piece 73 by means of which it may receive a movement against the tension of the spring 71 at right angles to the axis of the platen and may likewise be turned around its bearing 65. The right hand end plate 11 of the platen frame is formed with an upwardly extending portion 74 and three locking or engaging openings 75, 76 and 77 are formed in the edge thereof. A laterally projecting locking pin 78 extends from the regulating plate 68 and is adapted to be seated in any one of the engaging openings 75, 76 or 77. Thus, in order to adjust the plate 68 it is merely necessary to move the plate upwardly against the tension of its spring 71 and to give it a partial rotation in order to bring the locking pin 78 opposite the opening 75, 76 or 77 where it is desired to secure the plate, a stop pin 78^a being employed to prevent the plate from being moved too far forward. The locking pin may then be seated in the desired opening and the plate 68 will be maintained in this position against accidental displacement by the spring 71. Thus, the regulating plate 68 is provided with a laterally projecting stop pin 79 with which the pawl carrier 57 cooperates when the latter is in its normal position as indicated in Fig. 4. From this it will be understood that the position of the regulating plate 68 determines the initial position of the stop pin 79 and the stop pin 79 determines the initial position of the carrier 57 and consequently the line spacing pawl, and in this manner determines the extent of line spacing movement. If, for instance, an adjustment of the locking pin 78 in the engaging opening 77 is effected, then the line spacing pawl will have the shortest extent of throw and the line spacing wheel will be turned one tooth, whereas if the locking pin 78 is adjusted in the engaging opening 76 then the line spacing pawl will have a greater extent of movement and the platen will be rotated an extent corresponding to the distance between two teeth of the line spacing wheel,

whereas if the locking pin is adjusted in the engaging opening 75, the line spacing pawl will receive its greatest extent of throw and will rotate the platen to the extent corresponding to the distance between three teeth 70 of the ratchet wheel.

In Fig. 14 I have shown a different form of locking plate for retaining the adjustable plate 68 in position. Thus, instead of forming the locking or engaging openings 75, 76 75 and 77 directly in the right hand end plate 11 of the platen frame, as in the construction previously described, I employ a detachable plate 11^a which is secured to the right-hand end plate 11 by screws 11^b. This plate has locking openings 75^a, 76^a and 77^a cut in the upper edge thereof for the reception of the locking pin 78 as in the construction previously described and a stop 11^c, corresponding to the stop pin 78^a in the 85 previously described construction, is formed as a part of the plate 11^a to limit the forward swinging movement of the plate 68. The object of making the locking plate 11^a detachable is to enable the same line spacing 90 mechanism to be used in connection with any of the different characters of line spacing wheels now in use; some having twenty-nine teeth, some thirty-three and so on, the teeth being differently spaced and of different sizes in different wheels. When a line spacing wheel of one character is substituted for another in my machine it is merely necessary to detach one plate 11^a and substitute another having the openings therein 95 for it and no other change in the mechanism is necessary.

From the foregoing it will be seen that the line spacing pawl at the last portion of its movement is always brought to a given 105 point, although the initial position of the pawl is varied in order to change the extent of line spacing movement to be given to the platen. As heretofore pointed out the line spacing pawl is pivoted intermediate of its 110 ends, one end of the pawl being formed with an engaging nose 80 which cooperates with the teeth of the line spacing wheel, whereas the tail 81 of the pawl is formed with a cam-like surface 82 which is adapted to cooperate 115 with the detent roller 24 at the last portion of the line spacing movement and to force said detent toward the axis of the platen and thus into more firm engagement with the line spacing wheel. The pressure thus 120 exerted at the same time forces the engaging nose 80 of the line spacing pawl into firmer engagement with the teeth of the line spacing wheel, thereby preventing any liability of overthrow of the platen by a violent actuation of the line spacing mechanism. A stop pin 83 projects inwardly from the right hand end plate 11 of the platen frame and projects into the path of the carrier 57 for 125 the line spacing pawl as indicated in Fig. 6. 130

These parts are brought into coöperation after the cam 82 on the pawl has exerted pressure on the detent roller and their coöperation prevents the entire force of the line spacing movement of the pawl and carrier from being taken up by the detent roller. A stop pin 84 is riveted to the pawl as shown in Fig. 12 and projects laterally therefrom through a hole 85 in the carrier, which hole 10 is slightly larger than the diameter of the pin, thus affording a limited extent of movement of the pawl about the pivot 56 independently of its carrier, in order to enable the pawl to be moved into and out of engagement with the teeth of the line spacing wheel and then to effect a bodily movement of the pawl and carrier through the pressure applied to the pawl.

In the operation of the device the regulating plate 68 may be adjusted so that the locking pin 78 thereon is seated in one of the engaging openings 75, 76 or 77, in order to determine the extent of line spacing movement. The adjustment of the regulating plate in the manner hereinbefore described will determine the normal position of the finger piece 45 as indicated at *a*, *b* or *c* in Fig. 3. An actuation of the finger piece 45 thereafter will carry it to the position indicated at *d*, thereby turning the crank arm 30, and the turning movement of the crank arm will effect an actuation of the angular lever 50 which will produce a rearward movement of the link 53, thus first vibrating the pawl 55 around its pivot 56, so as to first move the pawl from the dotted to the full line position shown in Fig. 5, in order to effect an engagement between the pawl and the line spacing wheel at the first portion of the movement of the pawl. After this engagement has been effected a further movement of the link 53 will effect a movement of the pawl, its carrier and the line spacing wheel about the axis 21 until the pawl coöperates with the detent roller 24 and the carrier 57 is brought into coöperation with the fixed stop 83 when further movement of the parts is prevented. When pressure on the finger piece 45 is released the restoring spring 35 will turn the crank arm 30 back to the initial position, thereby turning the angular lever 50 to its initial position, withdrawing the pawl 55 from engagement with the line spacing wheel and restoring the pawl and its carrier to the normal position.

It will be observed that the construction is such that the line spacing mechanism is carried in part by the platen frame and in part by the carriage, and that, nevertheless, 60 the platen frame may be shifted independently of the carriage to either case position without affecting the action of the line spacing mechanism. During the shifting movement of the platen to change the case position thereof, the line spacing ratchet wheel,

its carrier and regulating plate are vibrated with the platen and platen frame, the link 53 vibrating around the pivot 52, whereas the actuating device or angular lever 50 and the rock shaft 29 remain relatively fixed on the carriage. It will also be seen that notwithstanding this relative movement between different parts of the line spacing mechanism the parts are positively connected throughout and that there is no opportunity for lost motion or improper action of the mechanism. It will also be seen that the angular lever 50 is pivoted to swing in a vertical plane that extends fore and aft of the machine, whereas the crank arm 30 and the ball 46 carried thereby, swing in a vertical plane that extends transversely of the machine or at right angles to the plane of movement of the lever 50. It will be understood, therefore, that during the actuation of the line spacing mechanism, a downward movement of the crank arm 30 will transmit movement to the angular lever 50 and that during this movement of the parts the ball 46 will receive a sliding movement 75 on the crank arm or pin 30, longitudinally thereof, and will at the same time receive a turning movement around the pin 30 and will also receive a sliding movement longitudinally of the slot 47 and will turn in the 80 bearing walls 48 of the slot. In one aspect of the invention the connection between the rock shaft 29 and the lever or actuating device 50, constitutes a pin and slot connection. From another aspect of the invention 85 said connection constitutes a universal joint or ball and socket connection, and from still another aspect of the invention the connection constitutes a combined universal joint and sliding or pin and slot connection between the parts in question. 90

Various changes may be made without departing from my invention.

What I claim as new and desire to secure by Letters Patent, is:—

1. In a typewriting machine, the combination of a platen, a line spacing ratchet wheel connected therewith, a line spacing pawl that coöperates with said ratchet wheel, a rock shaft for actuating said pawl, a finger piece 100 for actuating said rock shaft, a crank arm on the rock shaft, a lever actuated by said crank arm, a ball and socket connection between said crank arm and lever, and operative connections between said lever and line spacing pawl.

2. In a typewriting machine, the combination of a platen, a line spacing ratchet wheel connected therewith, a line spacing pawl that moves in the same plane as the 110 wheel and coöperates therewith, a rock-shaft that extends fore and aft of the machine, an angular extension on said shaft that constitutes a finger piece for turning said shaft, and intermediate mechanism between said 115 120 125 130

5 pawl and shaft for causing the turning movement of the shaft to effect a movement of the pawl in the general direction of the axis of said shaft, said intermediate mechanism including a pin and slot connection between the parts.

3. In a typewriting machine, the combination of a platen, a line spacing wheel connected therewith, a line spacing pawl, a rock shaft that extends fore and aft of the machine, a finger piece for turning said shaft, an angular lever, a pin and slot connection between the rock shaft and angular lever, and operative connections between the angular lever and pawl.

4. In a typewriting machine, the combination of a platen, a line spacing wheel connected therewith, a line spacing pawl, a rock shaft that extends fore and aft of the machine, a finger piece for turning said shaft, an angular lever that vibrates in a plane that extends fore and aft of the machine and has a slot therein, a crank arm that projects from said rock shaft and extends into said slot in the angular lever, and connections between said angular lever and pawl.

5. In a typewriting machine, the combination of a platen, a line spacing wheel connected therewith, a line spacing pawl, a hand actuated line spacing rock shaft, an angular lever, a pin and slot connection between the rock shaft and angular lever, and connections between the angular lever and line spacing pawl.

35 6. In a typewriting machine, the combination of a platen, a line spacing wheel connected therewith, a line spacing pawl, a rock shaft that extends fore and aft of the machine, a crank arm that extends from said 40 rock-shaft and constitutes a finger piece for turning it, an angular lever that vibrates in a vertical plane extending fore and aft of the machine, one arm of said angular lever having a slot therein, a crank arm on said 45 rock shaft, said crank arm having a spherical head which is received in the slot in said angular lever, and connections between said angular lever and pawl.

7. In a typewriting machine, the combination of a platen, a line spacing wheel connected therewith, a line spacing pawl, a hand actuated line spacing rock shaft, an angular lever having a slot in one arm thereof, a crank arm on the rock shaft, said 55 crank arm having a spherical head which is maintained in the slot in said angular lever, and connections between said angular lever and pawl.

8. In a typewriting machine, the combination of a platen, a line spacing ratchet wheel connected therewith, a pivoted carrier, a line spacing pawl which moves in the same plane as the wheel and which is pivoted to said carrier, a rock-shaft, a lever 65 that is actuated by said rock shaft, a link

connecting the said lever and line spacing pawl, and a finger piece connected to said rock shaft for actuating it.

9. In a typewriting machine, the combination of a platen, a line spacing ratchet 70 wheel connected therewith, a pivoted carrier, a line spacing pawl that moves in the same plane as the wheel and that is pivoted to said carrier, a rock shaft that extends fore and aft of the machine, an extension on said shaft that constitutes a finger piece for turning said shaft, and intermediate mechanism between said pawl and shaft for causing the turning movement of the shaft to effect a movement of 80 the pawl in the general direction of the axis of said shaft to bring the pawl into engagement with the line spacing wheel and then to move the pawl, line spacing wheel and carrier together, said intermediate mechanism comprising an actuating lever, and a pin and slot connection between said rock shaft and said lever.

10. In a typewriting machine, the combination of a platen, a line spacing wheel connected therewith, a line spacing pawl, a carrier which is pivoted on the axis on which the platen turns and to which said pawl is pivoted, a rock shaft that extends fore and aft of the machine, a finger piece for turning said shaft, and an angular lever that is actuated by said shaft and is operatively connected to the pawl and moves said pawl into engagement with the line spacing wheel and then moves the pawl carrier and 100 line spacing wheel together.

11. In a typewriting machine, the combination of a platen, a line spacing wheel connected therewith, a line spacing pawl, a carrier that is pivoted on the axis on which the platen turns and to which said pawl is pivoted, a rock shaft that extends fore and aft of the machine, a finger piece for turning said shaft, an angular lever that vibrates in a plane that extends fore and aft of the 105 machine and has a slot therein, a crank arm that projects from said rock shaft and extends into said slot in the angular lever, connections between the angular lever and pawl.

12. In a typewriting machine, the combination of a platen, a line spacing wheel connected therewith, a line spacing pawl, a carrier pivoted on the axis on which the platen turns and to which said pawl is pivoted, a 120 hand actuated line spacing rock-shaft, an angular lever, a pin and slot connection between the rock shaft and angular lever, and connections between the angular lever and line spacing pawl.

13. In a typewriting machine, the combination of a platen, a line spacing wheel connected therewith, a line spacing pawl, a carrier that is pivoted on the axis on which the platen turns and to which said pawl is piv- 130

oted, a hand actuated line spacing rock shaft, an angular lever having a slot in one arm thereof, a crank arm on the rock shaft, said crank arm having a spherical head thereon and being adapted to be received in the slot in said angular lever, and a link between said angular lever and pawl.

14. In a typewriting machine, the combination of a platen, a line spacing wheel connected therewith, a line spacing pawl co-operating with said line spacing wheel, and hand actuated means for actuating said pawl, said hand actuated means comprising a combined universal joint and pin and slot connection.

15. In a typewriting machine, the combination of a platen, a line spacing wheel connected therewith, a line spacing pawl co-operating with said line spacing wheel, a hand actuated rock shaft, and intermediate connections between the rock shaft and line spacing pawl, said connections comprising a combined universal joint and pin and slot connection.

16. In a typewriting machine, the combination of a platen, a line spacing wheel connected therewith, a line spacing pawl co-operating with said line spacing wheel, a hand actuated rock shaft, and intermediate connections between the rock shaft and line spacing pawl, said connections comprising a crank arm on the rock-shaft, a spherical head on the crank arm, a lever having a slot with grooved walls in which said spherical head is seated, and operative connections between said lever and said pawl.

17. In a typewriting machine, the combination of a platen, a line spacing wheel connected therewith, a line spacing pawl co-operating with said line spacing wheel, a hand actuated rock shaft, and intermediate connections between the rock shaft and line spacing pawl, said connections comprising a crank arm on the rock shaft, a spherical head loosely seated on the crank arm, a lever having a slot with grooved walls in which said spherical head is seated for turning and sliding action, and operative connections between said lever and said pawl.

18. In a typewriting machine, the combination of a platen, a line spacing wheel connected therewith, a line spacing pawl co-operating with said line spacing wheel, a rock shaft, a finger piece connected to said rock shaft, a crank arm, a spherical head loosely mounted on said crank arm, an angular lever having a slot in which said spherical head is seated and adapted to turn and slide, said angular lever being pivoted to vibrate in a vertical plane, and operative connections between said angular lever and said line spacing pawl.

19. In a typewriting machine, the combination of a platen, a line spacing wheel connected therewith, a line spacing pawl co-

operating with said line spacing wheel, a pivoted carrier to which the line spacing pawl is pivoted, an actuating device having a slot therein, an operative connection between said actuating device and said pawl, and a hand actuated swinging spherical head which is seated in the slot in said actuating device and transmits movement thereto.

20. In a typewriting machine, the combination of a platen, a line spacing wheel connected therewith, a line spacing pawl co-operating with said line spacing wheel, an angular lever having a slot therein, operative connections between said angular lever and pawl, and a hand actuated swinging spherical head which is seated in the slot in said lever and transmits movement thereto.

21. In a typewriting machine, the combination of a platen, a line spacing wheel connected therewith, a line spacing pawl co-operating with said line spacing wheel, a finger piece, intermediate connections between the finger piece and pawl, said intermediate connections comprising a pivoted actuating device having a slot therein, and a pivoted ball carrying device, said actuating and ball carrying devices swinging in planes that are at substantially right angles to each other and the ball on the ball-carrying device being seated in the slot in said actuating device.

22. In a typewriting machine, the combination of a line spacing pawl, and means for actuating it, said actuating means comprising two members that swing in planes at substantially right angles to each other, one of said members having a slot therein and the other of said members having a spherical head that is seated and works in said slot.

23. In a typewriting machine, the combination of a line spacing pawl, and means for actuating it, said actuating means comprising two members that swing in planes at substantially right angles to each other, one of said members having a slot therein and the other of said members having a loosely mounted spherical head that is seated in said slot and turns and slides therein.

24. In a typewriting machine, the combination of a platen, a line spacing wheel connected therewith, a co-operating line spacing pawl, a rock shaft that extends fore and aft of the machine, a finger piece connected to said rock-shaft, a crank arm on said rock shaft, a ball mounted to turn and to slide on said crank arm, an actuating device having a slot that forms a socket in which said ball turns and is adapted to slide, and connections from said actuating device to said pawl.

25. In a typewriting machine, the combination of a platen, a line spacing wheel connected therewith, a co-operating line spacing pawl, a rock shaft that extends fore and aft of the machine, a finger piece connected

to said rock shaft, a crank arm on said rock shaft, a ball mounted to turn and to slide on said crank arm, an actuating device having a slot that forms a socket in which said ball turns and is adapted to slide, a pivoted carrier to which the pawl is pivoted and a link between the pawl and said actuating device.

26. In a typewriting machine, the combination of a platen, a line spacing wheel connected therewith, a coöperating line spacing pawl, a spring restored rock shaft that extends fore and aft of the machine, a finger piece connected to said rock shaft, a crank arm on said rock shaft, a ball mounted to turn and to slide on said crank arm, an angular lever, having a slot that forms a socket in which said ball turns and is adapted to slide, a pivoted carrier that turns on an axis coincident with the axis of the platen and to which the pawl is pivoted, and a link between the pawl and said angular lever.

27. In a typewriting machine, the combination of a platen, a line spacing wheel connected therewith, a coöperating line spacing pawl, a rock shaft that extends fore and aft of the machine, a finger piece connected to said rock shaft at substantially right angles thereto, a crank arm on said rock shaft that vibrates in a transverse plane, a ball mounted to turn and to slide on said crank arm, an actuating lever having a slot that forms a socket in which said ball turns and is adapted to slide, said lever vibrating in a plane that extends fore and aft of the machine, and connections from said lever to said pawl.

28. In a typewriting machine, the combination of a platen, a line spacing wheel connected therewith, a coöperating line spacing pawl, a spring restored rock-shaft that extends fore and aft of the machine, a finger piece connected to said rock shaft at substantially right angles thereto, a crank arm on said rock shaft that vibrates in a transverse plane, a ball mounted to turn and to slide on said crank arm, an angular lever having a slot that forms a socket in which said ball turns and is adapted to slide, a pivoted carrier that swings in a vertical plane that extends fore and aft of the machine and turns on an axis coincident with the axis of the platen and to which the pawl is pivoted, and a link between the pawl and said angular lever.

29. In a typewriting machine, the combination of a line spacing pawl, and means for actuating it, said actuating means comprising two pivoted members, one of said members carrying a ball that is mounted to slide and turn on said member, and the other member having a slot in which said ball is seated and adapted to slide and turn.

30. In a typewriting machine, the combi-

nation of a line spacing pawl, and means for actuating it, said actuating means comprising two members united by a ball and socket and sliding connection, one of said members having a slot therein which forms a socket 70 and slideway for the ball and which has an enlarged opening in one portion thereof for the introduction of the ball.

31. In a typewriting machine, the combination of a line spacing pawl, and means 75 for determining the extent of line spacing movement which may be given to said pawl, said determining means comprising an adjustable pivoted member that is mounted to move at substantially right angles to its 80 pivotal axis to release it from locking engagement.

32. In a typewriting machine, the combination of a line spacing pawl, and means for determining the extent of line spacing 85 movement which may be given to said pawl, said determining means comprising an adjustable pivoted member that has an enlarged pivotal bearing opening to enable it to be moved at substantially right angles to 90 its pivotal axis to release it from locking engagement.

33. In a typewriting machine, the combination of a line spacing pawl, and means for determining the extent of line spacing 95 movement which may be given to said pawl, said determining means comprising a fixed part having a plurality of engaging openings, an adjustable pivoted member that is mounted to move radially of its pivotal axis 100 as well as to turn, and a locking piece carried by said adjustable member and adapted to be seated in any one of said engaging openings.

34. In a typewriting machine, the combination of a line spacing pawl, and means for determining the extent of line spacing movement which may be given to said pawl, said determining means comprising a fixed part having a plurality of engaging openings, an adjustable pivoted member that has an enlarged pivotal bearing opening to 110 enable it to be moved at substantially right angles to its pivotal axis as well as to turn, and a locking piece carried by said adjustable member and adapted to be seated in any 115 one of said engaging openings.

35. In a typewriting machine, the combination of a line spacing pawl, and means for determining the extent of line spacing 120 movement which may be given to said pawl, said determining means comprising a fixed part having a plurality of engaging openings, an adjustable pivoted member that is mounted to move radially of its pivotal axis 125 as well as to turn, a locking piece carried by said adjustable member and adapted to be seated in any one of said enguging openings, and a spring which maintains the adjustable member against accidental radial displace- 130

ment and maintains the locking piece seated in an engaging opening.

36. In a typewriting machine, the combination of a line spacing pawl, a pivoted carrier therefor, and means for determining the extent of line spacing movement of the carrier, said determining means comprising an adjustable pivoted member co-acting with said carrier and mounted to move at substantially right angles to its pivotal axis to release it from locking engagement.

37. In a typewriting machine, the combination of a line spacing pawl, a pivoted carrier therefor, and means for determining the extent of line spacing movement of the carrier, said determining means comprising an adjustable pivoted member that has an enlarged pivotal bearing opening to enable it to be moved at substantially right angles to its pivotal axis to release it from locking engagement.

38. In a typewriting machine, the combination of a line spacing pawl, a pivoted carrier therefor, and means for determining the extent of line spacing movement of the carrier, said determining means comprising a fixed part having a plurality of engaging openings, an adjustable pivoted member that is mounted to move at substantially right angles to its pivotal axis as well as to turn, and a locking piece carried by said adjustable member and adapted to be seated in any one of said engaging openings.

39. In a typewriting machine, the combination of a line spacing pawl, a pivoted carrier therefor, and means for determining the extent of line spacing movement of the carrier, said determining means comprising a fixed part having a plurality of engaging openings, an adjustable pivoted member that has an enlarged pivotal bearing opening to enable it to be moved at substantially right angles to its pivotal axis as well as to turn, and a locking piece carried by said adjustable member and adapted to be seated in any one of said engaging openings.

40. In a typewriting machine, the combination of a line spacing pawl, a pivoted carrier therefor, and means for determining the extent of line spacing movement of the carrier, said determining means comprising a fixed part having a plurality of engaging openings, an adjustable pivoted member that is mounted to move at substantially right angles to its pivotal axis as well as to turn, a locking piece carried by said adjustable member and adapted to be seated in any one of said engaging openings, and a spring which maintains the adjustable member against accidental displacement at right angles to its pivotal axis and maintains the locking piece seated in an engaging opening.

41. In a typewriting machine, the combination of a platen, a line spacing wheel, a

detent therefor, a line spacing pawl, and means for forcing the line spacing pawl into contact with the detent.

42. In a typewriting machine, the combination of a platen, a line spacing wheel, a detent therefor, and a line spacing pawl pivoted intermediate of its ends, one end of the pawl engaging the line spacing wheel and the other end of the pawl engaging said detent at the end of the line spacing movement.

43. In a typewriting machine, the combination of a platen, a line spacing wheel, a detent therefor, and a line spacing pawl pivoted intermediate of its ends and having variable extents of movement depending on the character of line spacing desired but always arrested at the same point when the line spacing movement is completed, one end of the pawl engaging said detent at the end of the line spacing movement.

44. In a typewriting machine, the combination of a platen, a line spacing wheel, a spring pressed detent roller coöperating with said wheel, and a line spacing pawl that jams against said detent roller at the last portion of the throw of the pawl and prevents an overthrow of the platen.

45. In a typewriting machine, the combination of a platen, a line spacing wheel, a spring pressed detent roller coöperating with said wheel, and a line spacing pawl pivoted intermediate of its ends and one end of which engages the line spacing wheel and the other end of which jams against said detent roller at the last portion of the movement of the pawl, thus forcing the pawl into engagement with the wheel and jamming the detent roller against the wheel to prevent an overthrow of the platen.

46. In a typewriting machine, the combination of a line spacing pawl, a finger piece, and intermediate mechanism for transmitting movement from the finger piece to said pawl, said intermediate mechanism comprising a vibrator member that has a cylindrical stem-like portion, a loosely mounted ball mounted to turn and to slide on said stem-like portion, and a vibratory member having a slot, the walls of which conform to the curvature of the ball and in which slot said ball is seated and adapted to turn and slide.

47. In a typewriting machine, the combination of a carriage, a platen frame that shifts independently thereof for upper and lower case writing, a platen carried by the platen frame, a line spacing ratchet wheel connected with said platen, a line spacing pawl, a hand actuated rock shaft carried by the carriage, and intermediate positive connections between the rock-shaft and pawl for transmitting line spacing movements to the pawl and for affording shifting movements of the platen without affecting the line spacing mechanism.

48. In a typewriting machine, the combination of a carriage, a platen frame that shifts independently thereof for upper and lower case writing, a platen carried by the 5 platen frame, a line spacing ratchet wheel connected with said platen, a line spacing pawl carried by and movable with the platen frame in its shifting movements, a hand-actuated rock-shaft carried by the carriage, 10 and intermediate positive connections between the rock-shaft and pawl for transmitting line spacing movements to the pawl and for affording shifting movements of the platen without affecting the line spacing 15 mechanism.

49. In a typewriting machine, the combination of a carriage, a platen frame that shifts independently thereof for upper and lower case writing, a platen carried by the 20 platen frame, a line spacing ratchet wheel connected with said platen, a line spacing pawl carried by and movable with the platen frame in its shifting movements, a hand-actuated rock-shaft carried by the carriage, 25 and intermediate positive connections between the rock-shaft and pawl for transmitting line spacing movements to the pawl and for affording shifting movements of the platen without affecting the line spacing 30 mechanism, said intermediate connections comprising parts that are pivotally united and afford a relative movement of some of said parts independently of the other during the shifting of the platen frame and platen 35 to different case positions.

50. In a typewriting machine, the combination of a carriage, a platen frame that shifts independently thereof for upper and lower case writing, a platen carried by the 40 platen frame, a line spacing ratchet wheel connected with said platen, a line spacing pawl, a rock shaft carried by the carriage and extending fore and aft of the machine, a finger piece connected to said rock shaft 45 and a single movement of which from left to right will effect a line spacing movement of the platen and will move the carriage to the right, and intermediate positive connections between the rock-shaft and pawl for 50 transmitting line spacing movements to the pawl and for affording shifting movements of the platen without affecting the line spacing mechanism.

51. In a typewriting machine, the combination of a carriage, a platen frame that shifts independently thereof for upper and lower case writing, a platen carried by the platen frame, a line spacing ratchet wheel connected with said platen, a line spacing 55 pawl carried by and movable with the platen frame in its shifting movement, a rock-shaft carried by the carriage and extending fore and aft of the machine, a finger piece connected to said rock shaft and a single movement of which from left to right will effect 60

a line spacing movement of the platen and will move the carriage to the right, and intermediate positive connections between the rock-shaft and pawl for transmitting line spacing movements to the pawl and for 70 affording shifting movements of the platen without affecting the line spacing mechanism.

52. In a typewriting machine, the combination of a carriage, a platen frame that shifts independently thereof for upper and lower case writing, a platen carried by the platen frame, a line spacing ratchet wheel connected with said platen, a line spacing pawl carried by and movable with the platen 80 frame in its shifting movements, a rock shaft carried by the carriage and extending fore and aft of the machine, a finger piece connected to said rock shaft and a single movement of which from left to right will 85 effect a line spacing movement of the platen and will move the carriage to the right, and intermediate positive connections between the rock shaft and pawl for transmitting line spacing movements to the pawl and for 90 affording shifting movements of the platen without affecting the line spacing mechanism, said intermediate connections comprising parts that are pivotally united and afford a relative movement of some of said 95 parts independently of the others during the shifting of the platen frame to different case positions.

53. In a typewriting machine, the combination with a carriage and line spacing 100 mechanism of a locking plate detachably fixed to the carriage and which enables different characters of line spacing wheels to be substituted one for another by changing the locking plates.

54. In a typewriting machine, the combination of a carriage, a platen, a line spacing ratchet wheel connected therewith, a line spacing pawl, means for actuating it, and means for determining the extent of line 110 spacing movement of the platen, said determining means comprising a locking plate detachably fixed to the carriage.

55. In a typewriting machine, the combination of a carriage, a platen; a line spacing 115 ratchet wheel connected therewith; a line spacing pawl; means for actuating it; and means for determining the extent of line spacing movement of the platen, said determining means comprising an adjustable 120 stop, and a locking plate detachably fixed to the carriage and the adjustable stop being secured in its adjusted position by said locking plate.

56. In a typewriting machine, the combination of a carriage, a platen, a line spacing ratchet wheel connected therewith, a line spacing pawl, means for moving said pawl from different normal positions to a fixed point, and adjustable means for determinin- 125 130

ing the normal position of the pawl, said determining means comprising a device detachably fixed to the carriage, whereby one character of line spacing wheel can be substituted for another by changing the detachable device.

Signed at the borough of Manhattan, city

of New York, in the county of New York, and State of New York, this 25th day of January, A. D. 1906.
